UNITED STATES PATENT OFFICE.

ROY S. TROWBRIDGE, OF BUTLER, NEW JERSEY.

UNLOADING DEVICE FOR RUBBER REFINERS.

Application filed December 21, 1926. Serial No. 156,216.

This invention relates to unloading devices for rubber refiners and more particularly to an unloading device for the sheet forming rolls thereof.

As is well known to those familiar with the art, in rubber refining or reclaiming apparatus, in one stage of the manufacture, the rubber is fed between adjacent faces of a pair of hard faced highly polished rotating rolls, which are forced together under such pressure that the rubber in its passage therethrough is reduced to a sheet of .003 to .005 of an inch in thickness, which adheres to one of the rolls. From this roll, it is separated by a knife and the sheet thus produced carried on to the next machine for the next operation thereon. Under many circumstances, it is convenient that this sheet be formed into a roll of substantially three and one-half or four inches in diameter. An important object of the invention is to provide means whereby this sheet may be formed into the roll as it leaves the knife by means of which it is separated from the forming roll.

A further object of the invention is to produce a device of this character such that when the roll formed from the sheet attains a predetermined size, it will automatically break away and be discharged to a bin or conveyor, by means of which it may be transported to the machine performing the next operation.

A further object of the invention is the provision of a device of this character deriving its necessary motive power from the sheet forming the roll.

These and other objects I attain by the construction shown in the accompanying drawings, wherein for the purpose of illustration is shown a preferred embodiment of my invention and wherein:—

Figure 1 is a side elevation of a rubber refining machine embodying an unloading mechanism constructed in accordance with my invention;

Figure 2 is a section taken on the line 2—2 of Figure 1.

Referring now more particularly to the drawings, the characters R and R' generally indicate the rolls of the sheet forming machine of rubber refining apparatus. Adjacent faces of these rolls move in the same direction and rubber R'' is introduced between the rolls at the upper side thereof. The rolls are forced together with such pres-

sure that a sheet S of rubber is produced which adheres to the surface of the roll R until it reaches a separating knife K, by means of which it is peeled from the roll. The rolls R and R' are supported in a suitable frame F, which likewise serves to support the knife K.

In accordance with my invention, I provide upon the frame F a pair of journals 10 which are preferably adjustable toward and away from the axis of the roll R, as indicated at 11, and provide means for mounting the ends of a roller 12, which preferably extend along the full length of the roll R in parallel relation thereto and slightly beyond the ends of this roll. The extended ends of the roller 12 have secured thereto gears 13 and provide mountings for plates 14. The plates 14 beneath the roller 12 provide bearings 15 for the ends of a second roller 16, which has gears 17 secured thereto meshing with the gears 13 of the roller 12. One or both of the plates 14 are provided with an extension 18 projecting outwardly from the roll R. These extensions provide means for connecting with the plates a bias, at present indicated as a weight 19, whereby the plates 14 may be caused to rotate about the roller 12 as an axis to force the roller 16 into contacting relation with the outer surface of the sheet S which, at the point of contact of the roller 16, is still adhering to the surface of the roll R.

In operation of the apparatus, the sheet separated by the knife K, because of its extreme thinness and flexibility bends downwardly and comes into contact with the surface of the roller 12. The rollers 12 and 16 are so proportioned that their gears 13 and 17 with the peripheral speed of the roller 12 is the same as the peripheral speed of the roll R. The sheet coming into contact with the roller 12 is thrown against the back face of the sheet S immediately in advance of the knife and is thus formed into a roll which enlarges in size until its diameter is such that its axial center passes a vertical plane including the axis of the roller 12. At this time, the roll formed by the sheet and generally indicated at 20 will overbalance and pass over the roller 12, with the result that the sheet is torn off at the knife. The separated roll may fall to a means, generally indicated as a conveyor 21 for transporting this roll to a further operation (not

disclosed). By adjusting the roller 12 toward or away from the axis of the roll R, the size of the roll 20 formed by the sheet which leaves the machine may be regulated within the necessary limits.

As other means might be provided for driving the roller 12 and since a great measure of the necessary rotation is provided by the contact of the separated sheet with the outer surface of the sheet while still attached to the drum and, therefore, some other means might be provided for directing the separated sheet against the drum, I do not limit myself to the construction hereinbefore set forth except as hereinafter claimed.

I claim:—

1. The combination with the sheet forming roll of rubber refining apparatus and the knife for separating the sheet from the roll, of means adjacent the roll supporting the separated sheet and directing the same toward the surface of the roll at a point adjacent to and in advance of the knife whereby the rotation of the roll serves to rotate the separated end and form a roll therefrom.

2. The combination with the sheet forming roll of rubber refining apparatus and the knife for separating the sheet from the roll, of means adjacent the roll supporting the separated sheet and directing the same toward the surface of the roll at a point adjacent to and in advance of the knife whereby the rotation of the roll serves to rotate the separated end and form a roll therefrom, said means supporting the roll formed from the sheet until it attains a predetermined size, the roll then leaving said means by gravity.

3. The combination with the sheet forming roll of rubber refining apparatus, a knife for separating the sheet from the roll, of a roll forming roller adjacent to and paralleling the sheet forming roll adjacent to and below the knife, and means for rotating said sheet forming roll.

4. The combination with the sheet forming roll of rubber refining apparatus, a knife for separating the sheet from the roll, of a roll forming roller adjacent to and paralleling the sheet forming roll adjacent to and below the knife, and means for rotating said sheet forming roll and at substantially the same peripheral speed as and in the opposite direction from the sheet forming roll.

5. The combination with the sheet forming roll of rubber refining apparatus, a knife for separating the sheet from the roll, of a roll forming roller adjacent to and paralleling the sheet forming roll adjacent to and below the knife, and means for rotating said sheet forming roll including a second roller engaging the rubber covered surface of the sheet

forming roll and a driving connection between said rollers. 65

6. The combination with the sheet forming roll of rubber refining apparatus, a knife for separating the sheet from the roll, of a roll forming roller adjacent to and paralleling the sheet forming roll adjacent to and below the knife, and means for rotating said sheet forming roll and at substantially the same peripheral speed as and in the opposite direction from the sheet forming roll including a second roller engaging the rubber covered surface of the sheet forming roll and a driving connection between said rollers. 70 75

7. The combination with the sheet forming roll of rubber refining apparatus, a knife for separating the sheet from the roll, of a roll forming roller adjacent to and paralleling the sheet forming roll adjacent to and below the knife, means for rotating said sheet forming roll and means for adjusting the roller toward and away from the roll. 80 85

8. The combination with the sheet forming roll of rubber refining apparatus, a knife for separating the sheet from the roll, of a roll forming roller adjacent to and paralleling the sheet forming roll adjacent to and below the knife, means for rotating said sheet forming roll and at substantially the same peripheral speed as and in the opposite direction from the sheet forming roll and means for adjusting the roller toward and away from the roll. 90 95

9. The combination with the sheet forming roll of rubber refining apparatus, a knife for separating the sheet from the roll, of a roll forming roller adjacent to and paralleling the sheet forming roll adjacent to and below the knife, means for rotating said sheet forming roll including a second roller engaging the rubber covered surface of the sheet forming roll, a driving connection between said rollers and means for adjusting the first named roller toward and away from said roll. 100 105 110

10. The combination with the sheet forming roll of rubber refining apparatus, a knife for separating the sheet from the roll, of a roll forming roller adjacent to and paralleling the sheet forming roll adjacent to and below the knife, means for rotating said sheet forming roll and at substantially the same peripheral speed as and in the opposite direction from the sheet forming roll including a second roller engaging the rubber covered surface of the sheet forming roll, a driving connection between said rollers and means for adjusting the first named roller toward and away from said roll. 115 120 125

In testimony whereof I hereunto affix my signature.

ROY S. TROWBRIDGE.
